DISPLAY HOLDER FOR PHOTOGRAPHS OR THE LIKE

Robert H. Dembar, Croton, N.Y., assignor to Graphicana
Corporation, Ossining, N.Y.

Filed Mar. 2, 1971, Ser. No. 120,245

Term of patent 14 years

Int. Cl. D6—07
U.S. Cl. D6—234

FIG. 1 is a perspective view of a display holder for photographs or the like showing my new design;

FIG. 2 is a top plan view thereof;

FIG. 3 is a perspective view of one element thereof;

FIG. 4 is a perspective view of a modified form of the display holder for photographs or the like shown in FIG. 1; and

FIG. 5 is a top plan view of FIG. 4.

I claim:

The ornamental design for a display holder for photographs or the like, as shown and described.
